[57] CLAIM

The ornamental design for a combined shotgun stock and magazine, as shown and described.

DESCRIPTION

FIG. 1 is a perspective view of a combined shotgun stock and magazine, showing our new design;

FIG. 2 is a top plan view thereof;

FIG. 3 is an elevational view of one side thereof;

FIG. 4 is a bottom plan view thereof;

FIG. 5 is an elevational view of the other side thereof;

FIG. 6 is a rear elevational view thereof;

FIG. 7 is a front elevational view thereof;

FIG. 8 is a side elevational view thereof, showing a modification in which two magazines appear on a side; and,

FIG. 9 is a fragmentary sectional view taken on the line 9—9 in FIG. 8.

The shotgun shells shown in broken line in FIG. 9 are for the purpose of illustrating the position of extra shells during storage and form no part of the present design.
